DESIGN FOR A PORTABLE ELECTRIC LAMP

Henry M. Peters, Chicago, Ill.

Application August 3, 1937, Serial No. 70,810

Term of patent 3½ years

To all whom it may concern:

Be it known that I, Henry M. Peters, a citizen of the United States, residing at Chicago, in the county of Cook and State of Illinois, have invented a new, original, and ornamental Design for a Portable Electric Lamp, of which the following is a specification, reference being had to the accompanying drawing, forming part thereof, in which:

Fig. 1 is a side elevational view of a portable electric lamp, showing my new design.

Fig. 2 is a rear elevational view thereof on a smaller scale.

Fig. 3 is a top plan view of the base, the standard being shown in cross-section.

I claim:

The ornamental design for a portable electric lamp, as shown.

HENRY M. PETERS.
